Attorney

UNITED STATES PATENT OFFICE

SAMUEL SCHENKEL, OF BROOKLYN, NEW YORK

NURSING NIPPLE

Application filed January 30, 1932. Serial No. 589,923.

The present invention relates to new and useful improvements in nursing nipples.

Nursing nipples as commonly constructed, do not prevent discharge of milk or other fluid from the bottle to which they are attached when they are carried thereby. This condition necessitates the provision of separate stoppers or closing means for the bottle when the same are to be transported with the fluid contents therein, or if this practice is not followed, the fluid contents are likely to be discharged from the bottle to the nursing nipple during transportation thus causing considerable inconvenience.

It is one of the objects of the present invention to provide a closing means for nursing bottles which means is incorporated with a nursing nipple.

It is a further object of the invention so to construct a nursing nipple that it may be attached to a nursing bottle in such a manner as to completely close the same and prevent discharge of contents therefrom.

It is a still further object of the invention so to construct such a device that it will be of a highly sanitary character, cheap to manufacture, and easily manipulated.

With the above and other objects in view, reference will be had to the accompanying drawing, in which:

Figure 1, is a perspective view of a nursing bottle illustrating a nipple constructed in accordance with one form of the present invention attached thereto in bottle closing position,

Figure 2, is a detail sectional view of the bottle and nipple taken on the line 2-2 of Figure 1,

Figure 3, is a view in side elevation of that form of the nipple illustrated in Figures 1 and 2, and;

Figure 4, is a fragmentary sectional view illustrating a modified form of the invention.

Referring again to the drawing, and particularly to Figures 1 to 3 inclusive, the reference character 5 designates a nursing bottle having a neck 6 and a discharge mouth 7 all of which may be of standard or conventional construction.

The reference character 10 designates a nursing nipple constructed in accordance with the present invention and said nipple has the usual discharge opening 11 in its contracted end and a relatively large bottle mouth receiving opening 12 defined by a reinforced portion forming a bead 13 by means of which the nipple may be secured to the neck of the bottle.

In accordance with the present invention, I provide upon the side of the main body portion of the nipple 10 a recess 15. This recess 15 is preferably formed of the same material from which the nipple is formed and is of a resilient nature. The recess 15 has side walls 16 the edge of which is defined by a bead or the like 17 and the recess has a bottom wall 18 which serves to bridge and close the discharge mouth 7 of the nursing bottle when the device is placed thereon as illustrated in Figures 1 and 2.

In this form of the invention it is only necessary to stretch or distend the side walls of the recess 15 and place the same about the mouth of a nursing bottle and through the medium of their own resiliency, the side walls will maintain the nipple in bottle closing position in which position it is shown in Figures 1 and 2. When it is desired to use the nipple, it is removed and positioned upon the bottle in the ordinary manner.

In Figure 4 of the drawing, I have illustrated a modified form of the invention and in this form, the device includes a main body portion 20 having the ordinary contracted end 21 and enlarged ends 22 for attachment to a bottle. In this last mentioned form of the invention, however, the bottle closing means is in the form of a stopper 23 which stopper comprises preferably a solid plug projecting laterally from the side of the main body portion of the nipple. The plug 23 which forms the stopper is preferably formed integral with the body portion 20 of the nipple and is preferably located near the open end thereof although the specific location of this stopper is not an important part of the present invention so long as the stopper is of sufficient length to enter and close the dis-

charge mouth of a nursing bottle, and is so positioned with respect to the main body portion of the nipple as to be freely receivable within the discharge mouth of a nursing bottle.

From the foregoing, it will be apparent that the present invention provides a combined nursing nipple and bottle closing means combined in a single article of manufacture and that the nipple may be used either for the purpose of discharging the contents of the bottle in the ordinary manner, or to completely close the same during transportation of the bottle and when in this latter position, prevent accidental discharge of the contents of the bottle.

While the invention has been herein illustrated in a preferred form, it is to be understood that it is not to be limited to the specific construction herein shown, and may be practiced in other forms without departing from the spirit of the invention.

Having thus described the invention, what is claimed as new and what it is desired to secure by Letters-Patent of the United States, is:

1. A nursing nipple comprising a hollow body formed of thin stretchable material and having an open end adapted to receive the neck of a nursing bottle, and a nursing bottle closure formed of the same material and integral with the nursing nipple, and projecting from the side thereof.

2. A nursing nipple comprising a hollow body formed of thin stretchable material and having an open end adapted to receive the neck of a nursing bottle, and a nursing bottle closure formed of the same material and integral with the nursing nipple, and projecting from the side thereof, said nursing bottle closure comprising a projecting integral flange defined by a bead.

In testimony whereof I affix my signature.
SAMUEL SCHENKEL.
